Charles Stock INVENTOR
BY Victor J. Evans
ATTORNEY

UNITED STATES PATENT OFFICE

CHARLES STOCK, OF BALDWIN PARK, CALIFORNIA

TRAP NEST

Application filed March 20, 1929. Serial No. 348,544.

This invention relates to a trap nest, the general object of the invention being to provide means whereby a hen entering the nest will close the same so that another hen can 5 not enter, though the hen in the nest will open the same when she attempts to leave the nest.

A further object of the invention is to provide means for preventing the hen from 10 leaving the nest when it is desired to trap the hen therein.

This invention also consists in certain other features of construction and in the combination and arrangement of the several parts, to be hereinafter fully described, 15 illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a vertical sectional view 20 through the nest, showing the same in open position.

Figure 2 is a similar view, showing the same in closed position.

Figure 3 is a section on line 3—3 of Figure 1.

In these views, the numeral 1 indicates a casing and the numeral 2 indicates a tiltable member placed in the casing at the bottom thereof, this member consisting of a 35 nest part 3 and a platform part 4, this part 4 being at the front of the part 3. Trunnions 5 pivotally support the member 2 in the casing and a door 6 has its inner end parts pivotally connected with the front of the casing, as shown at 7, this door being 40 engaged by an upright part 8 at the front end of the part 4.

These parts are so arranged that a hen 45 can pass into the casing by walking over the door part 6. The hen then passes over the part 4 and steps into the part 3. The weight of the hen will cause this part 3 to drop so that the part 4 is raised and the raising of this part will cause the upright 50 8 to move the door into closed position, as

shown in Figure 2. Then when the hen attempts to leave the nest by walking toward the slatted door part 6, her weight on the platform 4 will cause the member 2 to assume its first position, as shown in Figure 55 1, which will cause the door part to drop to open position so that the hen can pass from the nest. As will be seen from Figure 2, the member 2 always assumes a tilting position so that the eggs therein will roll toward the front of the nest part so that the weight of the eggs will not act to hold the parts with the door in closed position. 60

As will be seen, the sides of the nest part 65 are extended to form the side pieces of the platform, and a cross piece is fastened to the extended parts of the side pieces and another cross piece is fastened to the top of the front end of the nest piece to complete the platform. The upright part 8 70 is fastened to the front ends of the side pieces.

This arrangement places the top of the platform at the top of the nest, so that the hen can readily enter the nest from the 75 platform.

When it is desired to trap a hen in the nest, a spring member 9 is swung downwardly so that it will engage the upper rear edge of the nest part 3 when the same is lowered 80 under the weight of the hen and thus prevent the upward movement of said part when the hen attempts to leave the nest. Thus the hen will be trapped in the nest and will remain therein until she is released, by one opening the door 10 in the top of the casing 1 and by moving the member 9 to releasing position. 85

It is thought from the foregoing description that the advantages and novel features 90 of the invention will be readily apparent.

It is to be understood that changes may be made in the construction and in the combination and arrangement of the several parts, provided that such changes fall 95 within the scope of the appended claim.

What I claim is:—

A nest of the class described comprising a casing having its front open, a door member pivotally connected with the casing and 100

moving to an open position under the action of gravity, a nest in the casing and having its sides extended forwardly, cross pieces on the extended sides forming a platform, means for pivotally supporting the nest in the casing an appreciable distance from its front end, an upright piece connected with the ends of the extensions and engaging the door to raise the same to closed position when the nest is occupied the pivoted end of the door member engaging a part of the platform to limit the upward movement of the front end of the nest and to hold the same in a forwardly tilted position while the door is closed.

15 In testimony whereof I affix my signature.
CHARLES STOCK.
